UNITED STATES PATENT OFFICE.

WALTER ECKERSALL, OF HYDE PARK, ILLINOIS.

BURGLAR-ALARM.

SPECIFICATION forming part of Letters Patent No. 334,761, dated January 26, 1886.

Application filed April 18, 1884. Renewed October 27, 1885. Serial No. 181,100. (No model.)

To all whom it may concern:

Be it known that I, WALTER ECKERSALL, a subject of the Queen of Great Britain, residing at Hyde Park, in the county of Cook 5 and State of Illinois, have invented certain new and useful Improvements in Burglar-Alarms, of which the following is a specification, to wit:

This invention relates to an improvement in 10 burglar-alarms; and it consists in certain peculiarities of the construction and arrangement of the same, substantially as will be hereinafter more fully described and claimed, whereby the door is fastened by the releasing 15 of the alarm.

In order to enable others skilled in the art 20 to which my invention appertains to make and use the same, I will now proceed to describe its construction and operation, referring 25 to the accompanying drawings, in which—

Figure 1 is an elevation of a door having 25 my invention attached. Fig. 2 is an edge view of the door partly opened and the stop-bolt in engagement, and Fig. 3 is a view of a 30 catch-piece intended for use with this device upon windows.

A represents a door, and B the frame, of 30 any of the usual and well-known forms. Upon the door is secured a gong or bell, C, and 35 in close relation thereto an ordinary clock-alarm mechanism, C', having a hammer, c. This mechanism is so old and well known that it is deemed unnecessary to show it in detail in the drawings. Upon the door, adjacent to 40 the hammer c, is secured a spring-bolt, D, having its rear end turned outward, as at d, to engage the hammer and hold it stationary. The case d' of the bolt is formed with a slot, d'', through which projects a stud, e, having a 45 thumb-nut, e', by which the bolt may be held back when desired.

Upon the door-frame B is secured a casting, f, having a hole, f', in its outer end, as clearly shown in Fig. 2.

45 The operation of this device is evident from the drawings. During the day the bolt D is drawn back and secured by the set-nut, there-

by holding the hammer from any movement. At night the nut e' is loosened, thereby releasing the bolt, which rests against the casting 50 f, or the frame B. Should the door be opened during the night, the slightest movement will cause the bolt to register with the hole f' in the stop f, and the spring (seen in dotted lines in the drawings) throws it forward, effectually bolting the door, and at the same time 55 releasing the alarm, which notifies the occupants of the house of the attempt to enter.

The device is equally well adapted to windows or other places to be protected, and in 60 this case the alarm and bolt are placed upon the window-frame and the perforated stop piece or catch on the sash. The form of this stop may be varied at pleasure without interfering with the action of the device, only requiring a solid portion, against which the bolt 65 normally rests, and an opening into which it is sprung on being moved.

Having thus fully described my invention, what I claim as new, and desire to secure by 70 Letters Patent, is—

1. A door or window and its frame, one of which is provided with a clock-alarm mechanism, and a bolt adapted when drawn back to engage and hold the mechanism, and having 75 means for securing it in this position at will, in combination with a stop-catch, against which the end of the bolt rests, and provided with an opening into which it may spring on being moved, to secure the door or window 80 and sound the alarm, substantially as shown and described.

2. In a door and window alarm, the door or window A, bell C, clock mechanism C', having a hammer, c, and bolt D, having a set-nut, 85 e', in combination with the frame B, and stop f, having opening f', substantially as and for the purpose set forth.

In testimony whereof I affix my signature in presence of two witnesses.

WALTER ECKERSALL.
